UNITED STATES PATENT OFFICE.

WOLFGANG ERNEST SCHWARZMANN, OF SPRINGFIELD, MASSACHUSETTS, ASSIGNOR,
BY MESNE ASSIGNMENTS, TO AMERICAN BOSCH MAGNETO CORPORATION, OF NEW
YORK, N. Y., A CORPORATION OF NEW YORK.

MAGNETO.

Specification of Letters Patent. Patented June 29, 1920.

1,344,723.

Application filed October 12, 1918. Serial No. 257,841.

To all whom it may concern:

Be it known that I, WOLFGANG E. SCHWARZMANN, a citizen of the United States, residing at 51 Bellclaire avenue, 5 Long Meadow, Springfield, in the county of Hampden, State of Massachusetts, have invented certain new and useful Improvements in Magnetos; and I do hereby declare the following to be a full, clear, and exact 10 description of the invention, such as will enable others skilled in the art to which it appertains to make and use the same.

The present invention relates to magnetos of the sleeve type for igniting combustible mixtures in internal combustion engines, the sleeve having members of magnetic material and being rotated in the air gap between the armature and field poles of the magneto to alter or reverse the flux flowing from the 20 field magnet through the generating winding at the intervals of ignition.

Airplane engines are now made with 8 to 18 cylinders in V or "fan" arrangement with the two or three planes of cylinders spaced 25 apart differently than the usual angle, which, in the case of two planes, is 90° for 8 cylinders, 60° for 12 cylinders, or, in general, is equal to 360° or 720° divided by the number of cylinders. Other airplane engines 30 have their cylinders arranged in one or two circular series. In some of such engines, the departure from the usual spacing necessitates ignition at irregular intervals, that is at unequal angles of rotation; for instance, 35 an engine at present in use has 12 cylinders arranged in two planes on a 45° V, and requires ignition at 75°, 45°, 75°, 45°, and so on, inasmuch as the explosions occur in the cylinders of the two planes alternately.

Furthermore, the large number of cylinders, or the high speed of rotation of the engine, or both, necessitate such excessively rapid sparking that when a magneto is used it should produce more than the two sparks 45 per rotation generated by an ordinary bipolar magneto, because the speed of rotation of the magneto would otherwise be too high.

The object of my invention is to provide 50 a magneto which meets the foregoing requirements, and is, therefore, intended especially for association with an internal combustion engine of the V, "fan," "circular"

or other type, having many cylinders, or rotating at high speed, or both, wherein the power strokes occur at irregular intervals. 55 In accordance with my invention, I provide a magneto having an unsymmetrical magnetic circuit, that is one in which the trailing tips of the field and armature poles are disposed at irregular intervals around a circle, or a magneto having the field and armature poles and the members of the sleeve so constructed and arranged relatively to each other that upon rotation of the sleeve, the trailing tips of the sleeve members leave the 60 trailing tips of the field and armature poles at the unequally spaced intervals corresponding to the irregular ignition desired. Preferably, I do this by providing unsymmetrical field poles, or unsymmetrical armature poles, or both, the members of the sleeve being coordinated with those poles to break away therefrom at the irregular intervals, and thereby alter the magnetic flux in the generating winding. By altering the 75 electrical circuit of the generating winding at substantially those irregular intervals, as, for instance, by a mechanical interrupter on an electro-magnetic spark-plug, ignition voltages are generated at those intervals; 80 and by arranging the distributor to then connect the generating winding to the successive spark-plugs, ignition sparks are produced in the engine cylinders at the firing periods desired. 85

In the accompanying drawings illustrating my invention in application, as an example, to a high tension magneto having a bipolar field and armature and a sleeve for generating four ignition voltages per rotation for a 12-cylinder, 4-cycle engine with its cylinders on a 45° V, 90

Figure 1 represents a longitudinal cross section of one embodiment of my invention;

Fig. 2 is a transverse section of the magneto of Fig. 1;

Fig. 3 is a wiring diagram showing the mechanical interrupter and the distributor associated with the magneto;

Figs. 4 to 7 are diagrams showing the position of the rotatable sleeve at four successive ignition periods; and 100

Fig. 8 represents a modified construction. Referring particularly to Figs. 1 to 7, the

magnetic circuit of the magneto includes a stationary permanent magnet 1 with poles 2 and 3, and an armature core with poles 4 and 5 connected by the cross bar 6. The corresponding tips of the two field poles, and also of the two armature poles, are diagrammatically opposite, the armature poles being disposed in the field interpolar spaces so that the trailing tips of one are substantially 10 in radial line with the leading tips of the other. Furthermore, each field interpolar space, and thus each armature polar span, is substantially 67.5° in angular extent, and each field polar span, and thus each armature interpolar space, is substantially 112.5° . In general, these angular extents are substantially equal to the irregular intervals of firing of the engine multiplied by the ratio of the magneto speed to the engine 20 crank shaft speed, or, in this case, to 45° times $1\frac{1}{2}$, and 75° times $1\frac{1}{2}$, respectively.

The armature poles 4, 5 are abbreviated on opposite sides of the center line A—A of the cross bar 6; and the angular extents of 25 the portions of those poles as well as of the field poles 2, 3, are dissimilar in adjacent quadrants with respect to that line, but similar in alternate quadrants.

The magnetic sleeve has two iron members 8 magnetically separated from each other and held in position by the brass end plates 9. The members have a like span of about 72.5° , and are arranged to simultaneously bridge the field interpolar spaces, 35 and to later simultaneously leave the trailing tips of the armature poles.

The shafts 10, 11 of the sleeve are supported in ball bearings 12, 13 carried by the members 14, 15 which are secured to the base 40 plate of the magneto and are therefore rigid with respect to the poles of the field magnet 1. The shafts 16 and 17 of the armature are mounted in ball bearings 18, 19 carried in enlarged recesses of the two shafts of the 45 sleeve. The shaft 16 extends through and beyond the hollow shaft 10 and carries a collar 20 fast with it and with a stationary member 21 to secure the armature against rotation. The sleeve is rotated in its bearings by the gear 22, which is of proper size 50 to be driven from the crank shaft of the engine at the required speed ratio. As shown diagrammatically in Fig. 3, one terminal of the primary turns 23 of the generating winding 55 is connected to one terminal of the secondary turns 24 of the generating winding, and thence to the stationary insulated element 25 of the mechanical interrupter. The other terminal of the primary turns is 60 grounded, while the other terminal of the secondary turns is connected to the rotatable brush 26 of the distributor, which is driven by the gears 33, 34, at the required speed of 65 rotation, in this case at one-third the speed of the sleeve. The cam member of the me-

chanical interrupter is fast with the sleeve and has four cams 27 spaced apart 67.5° , 112.5° , 67.5° , and 112.5° , to deflect the grounded movable element 28 of the mechanical interrupter and thereby interrupt 70 the primary turns of the generating winding at the irregular intervals of ignition. At those intervals the distributor brush 26 engages the spark-plug distributing contacts 29, which are correspondingly irregularly 75 spaced to conduct the ignition currents from the generating winding to the insulated terminals of the spark-plugs 30 in the engine cylinders.

The position of the sleeve members at the 80 four irregular intervals of ignition are illustrated diagrammatically in Figs. 4 to 7 for the embodiment of the magneto shown in Figs. 1 to 3. In Fig. 4, the trailing tips of the members 8 of the sleeve are leaving 85 the trailing tips of the field poles 2, 3, thereby reducing the magnetic flux flowing through the cross bar 6, and therefore in the generating winding mounted thereon. Shortly after that moment, the magnetic 90 flux is established through the armature in the opposite direction, the flux thus being reversed in a small angle of rotation. At 67.5° later in the rotation, the trailing tips of the sleeve members 8 leave the trailing 95 tips of the armature poles 4, 5, as shown in Fig. 5, the flux previously flowing through the armature being reduced. At about 40° after this moment, the magnetic flux is established in the opposite direction through 100 the armature and thus completes the reversal of the flux therein, the leading tips of the sleeve members then being opposite the leading tips of the armature poles. At 112.5° after the second point of ignition, 105 or 180° after the first, the trailing tips of the sleeve members 8 again leave the trailing tips of the field poles 2, 3, as shown in Fig. 6; and at 67.5° later, or 180° from the second period of ignition, those tips leave 110 the trailing tips of the armature poles, as shown in Fig. 7. At each of these ignition periods, viz., at 0° , 67.5° , 180° and 247.5° from the position of the sleeve shown in Fig. 4, the mechanical interrupter opens the 115 circuit of the primary turns and the distributor brush engages the spark plug distributing contact to conduct the ignition current produced in the generating winding to the spark plug connected thereto. 120

In the modification in Fig. 8, the field poles 31 are symmetrical, instead of unsymmetrical, and each sleeve member 32 has a span of about 90° , which is slightly greater than the field interpolar space. The effect 125 of these changes is that, whereas the reversal of the magnetic flux in the armature when the sleeve members bridge the field interpolar spaces occurs in substantially the same angle of rotation as before, the re- 130

versal when the sleeve members bridge the armature interpolar spaces occurs more rapidly than before. In both modifications, but particularly in the latter one, the successive ignition voltages are sufficiently alike for practical purposes throughout the ordinary range of speed of the engine with which these magnetos are intended to be associated.

10 It is to be understood, of course, that various other forms of field and armature poles may be used, and that the sleeve members may also have other forms in coördination with the poles. Such modifications 15 are obviously within my invention which embodies an unsymmetrical magnetic circuit, or one in which the trailing tips of the sleeve members leave the trailing tips of the field and armature poles to give the 20 irregular intervals of ignition required by an engine of the kind hereinbefore referred to; the mechanical interrupter altering the circuit of the generating winding at said intervals.

25 Having thus described my invention, what I claim is:—

1. In a magneto for producing ignition currents at irregular intervals, a field magnet having poles, an armature having poles, 30 a sleeve rotatable in the air gap between the field and armature poles and having magnetic members magnetically separated from each other, the poles and the sleeve members being so constructed and arranged that the 35 trailing tips of the sleeve leave the trailing tips of the poles at irregular intervals, a generating winding, and means for altering the circuit of the generating winding at substantially said intervals.

40 2. In a magneto for producing ignition currents at irregular intervals, an unsymmetrical magnetic circuit, a generating winding, a magnetic sleeve rotatable in the air gap of said magnetic circuit to alter the 45 magnetic flux in the generating winding at the irregular intervals determined by the unsymmetrical magnetic circuit, and means for altering the electrical circuit of the generating winding at said intervals.

50 3. In a magneto for producing ignition currents at irregular intervals, an unsymmetrical magnetic circuit including a field magnet having poles and an armature having poles, a generating winding on the 55 armature, a magnetic sleeve rotatable in the air gap between the field and armature poles to alter the magnetic flux in the generating winding at the irregular intervals determined by the unsymmetrical magnetic circuit, and 60 means for altering the electrical circuit of the generating winding at said intervals.

4. In a magneto for producing ignition currents at irregular intervals, an unsymmetrical magnetic circuit including a field 65 magnet having poles and an armature hav-

ing unsymmetrical poles, a generating winding, a magnetic sleeve rotatable in the air gap between the field and armature poles, to alter the magnetic flux in the generating winding at the irregular intervals determined by the unsymmetrical magnetic circuit, and means for altering the circuit of the generating winding at said intervals.

5. In a magneto for producing ignition currents at irregular intervals, an unsymmetrical magnetic circuit including a field magnet having unsymmetrical poles and an armature having poles, a generating winding, a magnetic sleeve rotatable in the air gap between the field and armature poles 70 to alter the magnetic flux in the generating winding at the irregular intervals determined by the unsymmetrical magnetic circuit, and means for altering the circuit of the generating winding at said intervals.

6. In a magneto for producing ignition currents at irregular intervals, an unsymmetrical magnetic circuit comprising a field magnet having unsymmetrical poles and an armature having unsymmetrical poles, a 80 generating winding, a magnetic sleeve rotatable in the air gap between the field and armature poles to alter the magnetic flux in the generating winding at the irregular intervals determined by the unsymmetrical magnetic circuit, and means for altering the circuit of the generating winding at said intervals.

7. In a magneto for producing ignition currents at irregular intervals, a field magnet having poles, an armature having poles and a connecting cross bar, the angular extent of the portions of the field poles and of the armature poles being dissimilar in adjacent quadrants with respect to the center line of the cross bar, a magnetic sleeve rotatable in the air gap between the field and armature poles, and means for altering the circuit of the generating winding at 100 irregular intervals.

8. In a magneto for producing ignition currents at irregular intervals, a field magnet having poles, an armature having poles and a connecting cross bar, a generating winding, the angular extent of the portions of the field poles and of the armature poles being dissimilar in adjacent quadrants with respect to the center line of the cross bar, and being similar in alternate quadrants, a magnetic sleeve rotatable in the air gap 105 between the field and armature poles, and means for altering the circuit of the generating winding at recurring irregular intervals.

9. In a magneto for producing ignition currents at irregular intervals, a field magnet having poles, an armature having poles 115 abbreviated on opposite sides of the connecting cross bar therefor, a magnetic sleeve rotatable in the air gap between the armature 120

4
and field poles, a generating winding, and means for altering the circuit of the generating winding at irregular intervals.

10. In a magneto for producing ignition currents at irregular intervals, a field magnet having poles, an armature having poles with interpolar spaces different from the field interpolar spaces, a magnetic sleeve rotatable in the air gap between the field and armature poles, a generating winding, and means for altering the circuit of the generating winding at irregular intervals substantially equal to the interpolar spaces of the field and armature.

15. 11. In a magneto for producing ignition currents at irregular intervals, a field magnet having unsymmetrical poles, an armature having unsymmetrical poles with their tips substantially in radial line with respective tips of the field poles, a magnetic sleeve rotatable in the air gap between the armature and field poles, a generating winding, and means for altering the circuit of the generating winding at irregular intervals.

25. 12. In a magneto for producing ignition currents at irregular intervals, an unsymmetrical magnetic circuit including a field magnet having poles and an armature having poles, a magnetic sleeve rotatable in the air gap between the field and armature poles and comprising magnetically-separated magnetic members each having a span substantially equal to the field interpolar space, a generating winding, and means for altering the circuit of the generating winding at the irregular intervals determined by the unsymmetrical magnetic circuit.

30. 13. In a magneto for producing ignition currents at irregular intervals, a field magnet having unsymmetrical poles, an armature having unsymmetrical poles, a magnetic sleeve rotatable in the air gap between the field and armature poles, a generating winding, and means for altering the circuit of the generating winding at irregular intervals, each of the field interpolar spaces being substantially equal to one of the irregu-

lar intervals and each of the armature interpolar spaces being substantially equal to the adjacent one of the irregular intervals. 50

14. In a magneto for producing ignition currents at irregular intervals, a field magnet having poles different in span from its interpolar space, an armature having poles different in span from its interpolar space, 55 a magnetic sleeve rotatable in the air gap between the field and armature poles, a generating winding, and means for altering the circuit of the generating winding at the irregular intervals determined by the field and armature interpolar spaces.

15. In a magneto for producing ignition currents at irregular intervals, a bipolar field magnet having interpolar spaces each less than 90°, a bipolar armature having interpolar spaces each greater than 90°, a magnetic sleeve rotatable in the air gap between the field and armature poles and having two magnetic members each of a span substantially equal to the field interpolar 70 space, a generating winding, and means for altering the circuit of the generating winding at the irregular intervals determined by the interpolar spaces of the field and armature. 75

16. In a magneto for producing ignition currents at irregular intervals, an unsymmetrical magnetic circuit, a generating winding having primary and secondary turns, a magnetic sleeve rotatable in an air gap of said magnetic circuit, a mechanical interrupter for opening the electrical circuit of the primary turns at the irregular intervals determined by the unsymmetrical magnetic circuit, and a distributor having a 85 brush connected to one terminal of the secondary turns and also having stationary spark-plug distributing contacts arranged at angular intervals corresponding with the irregular intervals of operation of the mechanical interrupter. 80

In testimony whereof I affix my signature.

WOLFGANG ERNEST SCHWARZMANN.
